UNITED STATES PATENT OFFICE.

ELLA GOODWIN, OF CHICAGO, ILLINOIS.

WINDOW-CLEANER.

1,111,575.

Specification of Letters Patent. Patented Sept. 22, 1914.

Application filed December 15, 1913. Serial No. 806,737.

To all whom it may concern:

Be it known that I, ELLA GOODWIN, a citizen of the United States of America, and a resident of Chicago, county of Cook, and State of Illinois, have invented certain new and useful Improvements in Window-Cleaners, of which the following is a specification.

My invention relates to window cleaners and has for its object improvements in such 10 devices.

In the accompanying drawings Figure 1 is a side elevation with the cloth holding jaws in open position and with the handle folded to its shortest length; Fig. 2 is a 15 similar elevation with the jaws closed and the handle extended; Fig. 3 is an enlarged elevation of the upper part in the direction 3 of Fig. 1, the cloth being removed; Fig. 4 is a plan of Fig. 3; and Fig. 5 is an enlarged elevation, partly in section, of the upper part as it appears in Fig. 2, but with the cloth removed.

One of the objects of the present invention is to make a cleaner which will pass 25 easily through the narrow space between the glass of one sash and the adjacent rail of the other sash when the window is opened, for cleaning purposes, and to this end the device and its handle are made of sheet 30 metal so that the device as a whole has but little thickness and the handle is somewhat flexible. This flexibility avoids the necessity of the hand of the operator being forced against the glass when the head of the 35 cleaner passes through this narrow space, and the flexibility of the parts of the handle permits the jaws to be easily opened.

The handle consists of one long strip folded near the middle of its length as 40 shown at 10 in Fig. 1, and having secured on the ends of its branches or arms 11 and 12, the jaws 13 and 14. These jaws have teeth 15 for engaging and holding the washing cloth C. On the branches 11 and 12 is a 45 ferrule 16, which, when moved downward, permits the jaws to be opened for the insertion or removal of the cloth C. When the ferrule 16 is moved upward it forces the jaws together to grip the cloth as shown in 50 Fig. 2. One of these jaws is preferably lower than the other so that in closing they will pass each other and thus produce a thinner cleaner than would be the case if they met each other on the same horizontal 55 plane.

On the upper corner of the higher jaw 14 is a piece of rubber 17 which is held in place by wires 18, passing around the rubber 18 and through holes in the jaw 14 to the inner face of said jaw. The inner ends 60 of these wires are then twisted together as shown at 19 so as to draw the outer parts of the wire into the outer surface of the rubber 17. As thus secured the rubber is held without the ordinary clamping plates, and 65 the wire being embedded in the rubber does not touch the glass when the cleaner is used. When the rubber wears by use the wires may be drawn in farther by twisting the ends further. This may be readily done 70 with a pair of pliers.

To the handle composed of the parts 11 and 12 is secured a link 20 on which is hinged an arm 21 formed by folding a strip of sheet metal upon itself, the link being the 75 pivot at the point where the metal is bent back upon itself. The ends of this strip are secured together by a rivet 22. One end of the strip projects beyond the other end and is embraced by a ferrule 23 slideable on the 80 branch 12.

On the arm 21 is a sliding ferrule 24 which is prevented from slipping off the arm by a pin 25 secured to said arm near its free end. By slipping the ferrule 23 85 upward to release the free end of the arm 21, said arm may be turned on its pivot 20 from the position shown in Fig. 1 to that shown in Fig. 2, and the ferrule 24 may be slipped over the end of the main handle to 90 bind it to the arm 21. In this position the arm 21 becomes an extension to the main handle.

What I claim is—

1. In a window cleaner, a pair of flexible 95 arms of flat sheet metal, a pair of jaws secured to the upper end of said arms, and a flexible handle of flat sheet metal attached to and extending beyond the lower end of said pair of arms.

2. The combination with the head of a window cleaner, of a folding handle secured to said head, said handle being formed of thin flat metal and being flexible in both its folded and extended positions.

3. In a window cleaner, a handle formed of two flexible arms, cloth-holding jaws on the ends of said arms, a slideable ferrule for bringing the arms together to close the jaws, an arm pivoted to said handle and movable 110

from a position at the side of the handle to a position adjacent to the end of the handle to extend the length thereof, and devices for securing said pivoted arm in either 5 of its two positions.

4. In a window cleaner, a handle formed of two arms, jaws on the end of said arms, a ferrule on the arms to close the jaws, a flexible arm pivoted to the handle to extend

its length, and devices for securing the arm 10 in either of two positions.

Signed at Chicago, Illinois this 13th day of December 1913.

ELLA GOODWIN.
